CASKET HANDLE

Alred L. Gordon, Cleveland Heights, Ohio, assignor to Chicago White Metal Products, Inc., Chicago, Ill., a corporation of Illinois

Application February 24, 1949, Serial No. 78,113

2 Claims. (Cl. 16—111)

1

This invention relates to coffin hardware and particularly to coffin handles.

The primary object of this invention is to provide a coffin handle of the type comprising a fixed hand rail supported by spaced brackets that can be easily assembled, either before or after the support brackets are attached to the coffin.

Another object is to provide a coffin handle of the type stated that can be assembled and mounted without danger of scratching or marring the finish of the hand rail or coffin.

A further object is to provide a coffin handle having a detachable hand rail that is normally locked rigidly in place on its supporting brackets while at the same time being capable of easy disengagement therefrom.

Still another object is to provide a coffin handle that is simple, inexpensive and well adapted for the purpose intended.

These and other objects of the invention will become apparent from a reading of the following specification and claims together with the accompanying drawing wherein:

Figure 1 is a side elevation of a coffin having a handle made in accordance with this invention;

Figure 2 is a right end view of the same;

Figure 3 is a front view of a support bracket;

Figure 4 is a rear view of the same;

Figure 5 is a rear view of the support bracket shown in the Figure 4 with the hand rail locked in place;

Figure 6 is a longitudinal sectional view taken along the line and in the direction of the arrows 6—6 of the Figure 4;

Figure 7 is a longitudinal sectional view taken along the line and in the direction of the arrows 7—7 of the Figure 4;

Figure 8 is a vertical sectional view taken along the line and in the direction of the arrows 8—8 of the Figure 5;

Figure 9 is a front view of the locking key;

Figure 10 is a right end view of the same; and

Figure 11 is a top view of the same.

Referring to the Figure 1, there is shown a handle made in accordance with this invention as it appears when mounted on the front wall 11 of a conventional casket or coffin 10. A similar handle is mounted on the rear wall of the coffin; the coffin being lifted by means of the two handles.

The preferred form of handle illustrated comprises a hand rail 15 and its three supporting brackets 20.

The brackets are cast in bronze, brass or "white metal" and are provided with a suitable decorative design 21 as is the common practice in the art.

2

Each bracket 20 has a plane rear or posterior face 29 that is adapted to seat against the outer wall 11 of the coffin 10. Reference character 22 indicates mounting ears in which mounting screws are seated.

The bracket casting 20 has a laterally extending and depending arm 30 that is supported by the bracket body in parallel spaced relation with the coffin wall 11 as shown in the Figure 8.

10 A horizontal U-shaped channel 23 is cut in the posterior face 29 of the arm 30. The channel illustrated has upper and lower parallel walls, 34 and 35 respectively, joined by a vertical wall 33 positioned inwardly from the posterior face 29 of the bracket 20, and away from the side of the coffin 11 when the bracket is mounted thereon, as shown in the Figures 4, 6, 7 and 8. The height and width of the channel 23 is such that the hand rail 15 can be nested therein as shown in the Figures 3, 5 and 8. The cross-sectional configuration of the hand rail shown is that of a semi-flattened tube and the channel 23 is therefore rectangular in cross-section. However, if round or square tubing is used the shape of the channel 23 must be altered accordingly. A pair of opposed parallel slots or keyways 24 and 24a are cut in the upper and lower faces of the channel 23. These slots start at the rear edge of the channel and are angled toward the front as shown in the Figures 6 and 7. The starting point, or first end, of each slot is identified by the numeral 36, while the terminus, or second end, of each slot is identified by the numeral 37. A key 25 having bevelled edges 27 is slidably engageable with the slots 24 and 24a.

15 The hand rail 15 can be made of any suitable bar stock or tubing, and in the preferred form shown is made of tubular stock, for the sake of lightness. The tube is slightly compressed and provided with longitudinally extending decorative grooves 12 in order to improve its appearance.

20 Reference character 32 indicates decorative terminal plugs that cover the raw ends of the hand rail 15. The vertical wall of the channel 23 has horizontal concave grooves 31 cut therein that mate with the decorative grooves 12 of the hand rail 15 as shown in the Figures 4 and 8.

25 The hand rail 15 is attached to the bracket 20 by nesting the hand rail in the channel 23 as shown in the Figure 8. The key 25 is inserted in the aligned keyway slots 24 and 24a at their first ends 36 with its flat side 26 against the hand rail 15. The key 25 is then moved along the slots 24 and 24a whose angular disposition causes the key 25 to press progressively

firmer against the hand rail 15 as the key is moved along the keyway toward the second end thereof, 57, thereby securely wedging the hand rail 15 against the channel walls. An anvil-like handle 28 is provided on the key. This handle serves as a striking surface for driving the key along the keyway to obtain a greater wedging action. The mating grooves 12 and 31, of the hand rail and channel respectively, provide additional interlocking surfaces between the hand rail and bracket so that it is impossible for the hand rail to tilt or rattle in the bracket.

As will be noted from the foregoing disclosure the handle is assembled by nesting the hand rail 15 in the channel 23 of each of the support brackets 20. This is done by merely laying each bracket channel over the hand rail at the proper point and then securing the hand rail in place on the bracket by means of the key 25. The bracket 20 has no encircling ring or hole through which the hand rail has to be drawn, as is the case with other handles of this type.

In as much as the hand rails are usually completely finished and polished before assembly, the process of drawing the hand rails through such bracket holes often resulted in the nicking and scratching of the highly polished hand rails. The possibility of damaging the hand rail during assembly is completely eliminated with the instant invention.

The handle can also be assembled by first mounting the brackets 20 on the side of the coffin at the proper intervals with their channels 23 aligned as shown in the Figure 1. The hand rail 15 is then slipped between the bracket arm 30 and the coffin wall 11 and nested in the channels 23 of the brackets 20. Keys 25 are then inserted in each of the bracket keyways and wedged tightly against the back of the hand rail 15 as shown in the Figure 8.

Since there is no threading or sequential engagement of the brackets, the coffin wall cannot be accidentally marred by the hand rail as it is being secured to the brackets. The mounting of the handle on the coffin therefore can be done quickly, easily and without the time-consuming precautions necessary with other types of handles.

While the handle shown in the preferred form has three supporting brackets, the number of brackets may be increased or decreased to suit the length of the handle and the weight to be supported.

While the hand rail is securely wedged in place by the keys 25 so that the hand rail 15 and the brackets 20 become a single unit for all practical purposes, the hand rail can be released and removed, if so desired, by removing the keys 25. A new hand rail having a different finish or a different color can be easily substituted without removing the brackets 20 from the coffin.

It will now be clear that there is provided a device which accomplishes the objectives heretofore set forth. While the invention has been disclosed in its preferred form; it is to be understood that the specific embodiment thereof as described and illustrated herein is not to be considered in a limited sense as there may be other forms or modifications of the invention which should also be construed to come within the scope of the appended claims.

I claim:

1. A coffin handle, comprising in combination, a plurality of linearly aligned and spaced bracket members adapted to be mounted on the side of a

coffin, each of the said brackets having a laterally extending and dependent arm portion formed integral therewith, each of the said arms having spaced upper and lower horizontally extending parallel walls formed therein and connected by a vertical wall spaced inwardly from the posterior face of the said arm, the several walls together defining a horizontally extending U-shaped channel which intersects the aforesaid posterior face of the arm, the said upper and lower walls having oppositely positioned parallel slots therein, each of the said slots having a first end and a second end, the said aligned slots being angularly disposed with reference to the said vertical wall and nearer to the vertical wall at their second end than at their first end; a single longitudinally extending hand-rail positioned in the said channels of the several brackets, the thickness of the said hand-rail being greater than the distance between the second end of the slots and the vertical wall but less than the distance between the first end of the slots and the aforesaid vertical wall; and a key mounted in each pair of aligned slots in pressed engagement with the said hand-rail, whereby the hand-rail is caused to bear against the vertical wall of said channels in rigid locked engagement with the several brackets.

2. A coffin handle, comprising in combination, a plurality of linearly aligned and spaced bracket members adapted to be mounted on the side of a coffin, each of the said brackets having a laterally extending and dependent arm portion formed integral therewith, each of the said arms having spaced upper and lower horizontally extending parallel walls formed therein and connected by a vertical wall spaced inwardly from the posterior face of the said arm, the several walls together defining a horizontally extending U-shaped channel which intersects the aforesaid posterior face of the arm, the said upper and lower walls having oppositely positioned parallel slots therein, each of the said slots having a first end and a second end, the said aligned slots being angularly disposed with reference to the said vertical wall and nearer thereto at their second end than at their first end, the said vertical wall having a plurality of adjacent cavities in the face thereof; a single longitudinally extending hand-rail positioned in the said channels of the several aligned brackets and having a plurality of adjacent protuberances that interfit the said vertical wall cavities, the thickness of the said hand-rail being greater than the distance between the second end of the slots and the vertical wall but less than the distance between the first end of the slots and the aforesaid vertical wall; and a key mounted in each pair of aligned slots in pressed engagement with the said hand-rail, whereby the said hand-rail is caused to bear against the vertical wall of said channels in rigid locked engagement with the several brackets.
